UNITED STATES PATENT OFFICE.

LEON H. PRENTICE, OF WAUKEGAN, ILLINOIS.

DESIGN FOR A RADIATOR.

SPECIFICATION forming part of Design No. 17,270, dated April 19, 1887.

Application filed March 7, 1887. Serial No. 230,658. Term of patent 7 years.

To all whom it may concern:

Be it known that I, LEON H. PRENTICE, of Waukegan, in the State of Illinois, have invented and produced a new and original Design for Radiators, of which the following is a specification, reference being had to the accompanying drawing, forming part thereof.

The figure is a perspective view of my newly-designed radiator, this view being deemed sufficient to fully illustrate my design.

The leading feature of my design consists in the upright or vertical pipes of the radiator, having a comparatively plain or even surface for a portion of their length from the bottom up, and with an ornamented surface consisting, preferably, of embossed or depressed ornamentation at the top or upper part, the plain portion constituting the lower or base portion of the radiator, and the figured or ornamented portion constituting the top or crown of the same, the plain and figured portions offsetting each other, and presenting a contrasting appearance between the upper and lower parts of the radiator. These portions of the surface give the radiator a pleasing appearance.

A designates the lower portion of the radiator, composed of that portion of the vertical pipes or loops A' having the surface comparatively plain, the surface *a* being smooth and

having a single bead, *a'*; and B designates the upper part, composed of that portion of the pipes or loops ornamented with embossed figure-work *b*, in contrast with the lower portion.

The invention consists in the radiator composed of a series of vertical pipes or loops of uniform height, having the crown or top portion of the pipes or loops ornamented or figured a uniform distance from the top downward, the portion below being comparatively plain. In this manner the ornamented and plain portions of the aggregate surface of the radiator constitute two rectangular parallelograms, one above the other. A similar effect would be produced by transposing the plain and figured portions.

What I claim is—

The design for a radiator herein shown, consisting of a series of upright pipes or loops of uniform height, having the upper and lower portions of their aggregate surface distinguished from each other by ornamentation, so as to present rectangular figures A B in contrast.

LEON H. PRENTICE.
